UNITED STATES PATENT OFFICE.

ABRAHAM LINCOLN RICH, OF ALLEGHENY, PENNSYLVANIA.

BUSTLE.

SPECIFICATION forming part of Letters Patent No. 330,424, dated November 17, 1885.

Application filed January 28, 1885. Serial No. 154,333. (No model.)

To all whom it may concern:

Be it known that I, ABRAHAM LINCOLN RICH, a citizen of the United States, residing at Allegheny City, in the county of Allegheny and State of Pennsylvania, have invented certain new and useful Improvements in Bustles, of which the following is a full, clear, and exact description, reference being had to the accompanying drawings, forming part of this specification, in which—

Figure 1 represents a perspective view, and Fig. 2 represents a sectional view, of my improved bustle.

My invention relates to that class of bustles which are self-adjusting in their nature; and my invention consists in the peculiar construction and combination of the several parts, all of which I shall hereinafter fully describe and claim.

20 To enable others skilled in the art to make and use my improvement, I will now proceed to describe the exact manner in which I have carried it out.

Heretofore many of the bustles offered to the public have been constructed in such manner that the continued wearing of the bustle for a short time often injured it to such extent that it speedily became unfit for the use it was intended. This has sometimes been caused by the whalebone or metallic strips losing their tensile strength and becoming thereby weakened.

To overcome these difficulties is the object of my invention, and at the same time offer to the public a bustle which is cheap in its construction and especially adapted for the purpose intended.

35 To more fully develop my invention, I will now minutely describe its construction and operation.

In the said drawings, A represents a base-piece securely held in place by a series of curved transverse strips, A', any number of which may be used, and composed of any suitable material. At or near the center of the base-strip A, and secured to its upper surface by a hinge, a, is a standard, B, its upper end being hinged or otherwise loosely pivoted to a longitudinal frame-strip, C, and to this frame-strip is also secured a series of cross-strips, D.

By the arrangement of these several parts it is evident the outer and inner sections, as described, are adapted to fold, the outer sec-

tion moving forward and upward when pressure is brought to bear upon it. To cause these parts to assume their normal positions, it is necessary that means be employed for that purpose. It will be noticed that there is connected to the top of the standard a cord 55 or connection, b, its free end being attached to the upper end of the base A, and prevents the standard and frame-strips from moving too far in its backward movement; and this cord is of such length as to prevent the 60 standard from assuming a position at right angles to the base itself. Connected to the opposite end of the base-piece is an elastic cord or spring, E, its opposite end being attached to the top of the standard. This 65 spring-connection yields when the pressure is brought to bear upon the bustle, but immediately retracts itself when this pressure is relieved, and causes the bustle to assume its 70 normal position without deranging the wearer's clothes. Both ends of the base-strip and frame-strip are connected together by cords F and G. The length of said cords to a certain extent governs the shape of the bustle, and prevents the ends between the strips and 75 base from becoming too widely separated. From this description it is evident a bustle so constructed would be light, durable, and non-crushable, the different strips being composed of metal similar to corset-steels, and 80 the bustle may be covered with fabric to prevent injury to the wearer's clothes.

Having thus described my invention, what I claim as new, and desire to secure by Letters Patent, is—

1. As an improvement in bustles, the combination, with the base A and transverse strips A', of the frame, and cross-strips C and D, connected to the base, and a pivotally-secured standard, B, adapted to fold the two 95 sections when pressure is applied to the bustle, substantially as herein described.

2. In a bustle, the combination, with the base A and transverse strips A', of the frame-strip C, the cross-strips D, secured thereto, a standard, B, pivotally secured to the frame-strip and base, a spring, E, and the adjusting-cords b, F, and G, substantially as herein described.

ABRAHAM LINCOLN RICH.
